UNITED STATES PATENT OFFICE.

JOSEPH W. BISHOP, OF MUSKEGON, MICHIGAN, ASSIGNOR TO THE BRUNSWICK-BALKE-COLLENDER COMPANY, OF WILMINGTON, DELAWARE, A CORPORATION OF DELAWARE.

COMBINED PHONOGRAPH AND RADIO RECEIVING APPARATUS.

Application filed June 30, 1924. Serial No. 723,116.

This invention relates to a combination radio and phonograph apparatus and has for its primary object to provide means for employing a single amplifying horn with either the radio apparatus or the phonograph, as may be desired.

Another object is to provide means for changing over from use of the one apparatus to the other by a simple manipulation 10 of a knob or handle on the outside of the cabinet.

In the drawings in which I have shown one embodiment of my invention,

Fig. 1 is a front elevation of a cabinet in 15 which my invention may be embodied.

Fig. 2 is a front elevation of a part of the apparatus shown in dotted lines in Fig. 1.

Fig. 3 is a section on the line 3—3 of Fig. 1.

Fig. 4 is a section on the line 4—4 of Fig. 2, and

Fig. 5 is a section on the line 5—5 of Fig. 2.

As is well-known the use of radio receiving apparatus is widespread as is also the use of phonographs. One of the important considerations of a radio receiving set is the question of space and another consideration is the question of a proper amplifying horn.

A horn which will give good results is expensive and it is therefore my purpose to economize space and to make a single amplifying horn to serve for both a radio receiving set and a phonograph and thereby make it possible to mount both of the above instruments in a single cabinet, which may, of course, be made an ornamental piece of furniture.

Referring now to the drawings, 1 designates a cabinet of any suitable construction. Contained in said cabinet is a radio receiving device indicated generically at 2 and a phonograph indicated at 3 and comprising the usual turn-table 4, sound reproducer 5 and tone-arm 6. The tone-arm 6 is mounted on the motor-board 7 and is connected to the amplifying horn 8 beneath the motor-board, by means now to be described. Connected to the bell mouth of the horn 8 by any suitable means is a tubular, T-shaped neck 9 having arms 10, 11 and 12.

The arm 10 is connected to the horn in any suitable manner and extends upwardly and from said horn, and at its upper end it is

bent to one side to form a sleeve 13 having 55 an open end facing the wall 14 of the cabinet. The arm 11 is adapted to be connected to the radio loud speaker 15 and the arm 12 is adapted to be connected to the tone-arm 6 by means passing through the motor-board 7.

It will be evident that sounds may be transmitted from the phonograph or the radio loud speaker, selectively, to the amplifying horn by means of the arms 11 or 65 12 and the arm 10 of the neck. Revolubly mounted in the sleeve 13 is a valve 16 comprising a tubular member having walls 17 fitting within said sleeve 13 and also provided with an elbow 18 having an end 18' 70 registering with the arm 10 and an end 18'' registering with the arm 12 or with the arm 11.

It will be seen that the end 18' provides a continuous passage to the arm 10 and so to the amplifying horn, while the other end 18'' of the elbow may provide a passage to the arm 11 or 12, as may be desired, it being understood, of course, that the openings in the arms 11 and 12 are of the same size as 80 the opening in the end 18'' of the elbow. Therefore, a continuous passage may be provided from the horn to either the phonograph or the radio loud speaker, as may be desired, by merely turning the valve 16 from the position shown in Fig. 2, where it forms a passage between the phonograph and the horn to a position diametrically opposite thereto where it will furnish a passage from the horn to the radio loud speaker.

In this embodiment of my invention I provide means on the outside of one wall of the cabinet, as the wall 14, for example, to operate the valve and this means may comprise a knob or handle 19 connected to a rod 20 received in a slot 21 in a lug 22 on the valve 16. It will thus be apparent that the valve may be turned from the position shown in Figs. 1 and 2 to a position diametrically opposite thereto by merely turning the knob 19. By this turning of the knob 19 the valve also may be used to modify the sound coming from either the phonograph or the radio set by increasing or decreasing the volume thereof, as will 100 be apparent to those skilled in the art.

It will be seen that the sleeve 13 has its end parallel to the wall 14, that is, its end

faces said wall so that the valve is turned about a longitudinally and substantially horizontal axis by the manipulation of the handle 19. To limit movement of the valve, 5 so as to insure registry of the opening 18" with the arms 11 or 12 at the extreme limits of movement of the valve, I provide a stop 10 23 which may be a plate fastened on the end of the sleeve 13 and adapted to be engaged by shoulders 24 formed by cutting away a portion of the wall 17.

From the above it will be evident that I have provided a means for using an amplifying horn with either a phonograph or a 15 radio outfit, as may be desired, the changing over from one to the other being easily effected by a simple adjustment from the outside of the cabinet, and without necessitating even so much as the lifting of the 20 cover on the cabinet.

I am aware that changes in the form, construction and arrangement of parts may be made without departing from the spirit and without sacrificing the advantages of the 25 invention and I reserve the right to make all such changes as fairly fall within the scope of the following claims.

I claim:—

1. In a device of the class described, a 30 tubular sleeve mounted in a cabinet, a phonograph tone arm connected to said sleeve, a neck connecting said sleeve to an amplifying horn, an arm connecting said sleeve to a radio loud speaker, a tubular valve revolvably mounted in said sleeve having a circular opening in one end and in one side thereof, and means connected to the closed end of 35 said valve whereby said valve may be revolved to make the opening in the side coincide with either the arm or the tone arm to complete a passage to said amplifying horn.

2. In a device of the class described, a 40 tubular sleeve mounted in a cabinet, a phonograph tone arm connected to said sleeve, a neck connecting said sleeve to an amplifying horn, an arm connecting said sleeve to a radio loud speaker, and a tubular valve revolvably mounted in said sleeve and having a circular opening in one end thereof for maintaining a passage from the amplifying horn 45 to said sleeve, said valve also having an opening in one side thereof for cooperating with either the speaker arm or the tone arm for completing the passage to said amplifying horn.

3. In a device of the class described, a 50 tubular sleeve mounted in a cabinet, a phonograph tone arm connected to said sleeve, a neck connecting said sleeve to an amplifying

horn, an arm connecting said sleeve to a 60 radio loud speaker, a tubular valve revolvably mounted in said sleeve and having a circular opening in one end and in one side thereof, and means connected to the other end of said valve and extending through said 65 cabinet whereby said valve may be operated from the outside of said cabinet to make the opening on the side coincide with either the arm or the tone arm to complete a passage to the amplifying horn. 70

4. In a device of the class described, a tubular sleeve mounted in a cabinet, a phonograph tone arm connected to said sleeve, a neck connecting said sleeve to an amplifying horn, an arm connecting said sleeve to a 75 radio loud speaker, a tubular valve revolvably mounted in said sleeve and having a circular opening in one end and in one side thereof, means arranged on said sleeve for retaining said valve thereon, and means connected to the other end of said valve and extending through said cabinet whereby said valve may be operated on the outside of said cabinet to make the opening on the side coincide with either the arm or the tone arm 85 to complete a passage to the amplifying horn.

5. In a device of the class described, a tubular sleeve mounted in a cabinet, a phonograph tone arm connected to said sleeve, a 90 neck connecting said sleeve to an amplifying horn, an arm connecting said sleeve to a radio loud speaker, a tubular valve revolvably mounted in said sleeve and having a circular opening in one end and in one side 95 thereof, means arranged on said sleeve for retaining said valve therein, and means connected to the closed end of said valve whereby said valve may be revolved to make the opening in the side coincide with either the arm or the tone arm to complete a passage to the 100 amplifying horn.

6. In a device of the class described, a tubular sleeve mounted in a cabinet, a phonograph tone arm connected to said sleeve, a 105 neck connecting said sleeve to an amplifying horn, an arm connecting said sleeve to a radio loud speaker, a tubular valve revolvably mounted in said sleeve and having a circular opening in one end and in one side 110 thereof, and a rod connected to the closed end of said valve and extending through the side of the cabinet whereby said valve may be revolved to make the opening in the side coincide with either the arm or the tone arm 115 to complete a passage to said amplifying horn.

JOSEPH W. BISHOP.
